(57) **CLAIM**

The ornamental design for a vehicle wheel, as shown and described.

DESCRIPTION

FIG. 1 is a perspective view of a vehicle wheel, showing our new design; and

FIG. 2 is a front view thereof; and,

FIG. 3 is a section view taken along line 3-3 in FIG. 2. The broken line showing of the rear portion of the wheel, the bolt holes and the center hole in the central hub area is included for the purpose of illustrating environment and forms no part of the claimed design.

1 Claim, 2 Drawing Sheets

FIG 1
